UNITED STATES PATENT OFFICE.

WILLARD S. ATKINSON, OF ASHLAND, NEW JERSEY, ASSIGNOR TO ATLANTIC ELEVATOR COMPANY, OF PHILADELPHIA, PENNSYLVANIA, A CORPORATION OF PENNSYLVANIA.

ELEVATOR CONTROL MECHANISM.

Application filed April 29, 1921. Serial No. 465,554.

To all whom it may concern:

Be it known that I, WILLARD S. ATKINSON, a citizen of the United States, residing in Ashland, county of Camden, State of New Jersey, have invented certain new and useful Improvements in Elevator Control Mechanism, of which the following is a specification.

My invention relates to mechanism for governing or controlling an elevator car or the like in response to change of its speed.

In accordance with my invention, speed responsive means, as a centrifugal governor, responsive to the speed of the car, effects one or more controls, as reduction of speed of the motor or car-driving means, deenergization of the motor or cessation of application of driving power to the car, and setting into operation one or more safety devices.

Further in accordance with my invention, a centrifugal governor is provided with both weight and spring controls, whereby throughout a lower speed range the weight control alone is effective, and for a higher speed range the spring control comes into operation.

My invention resides in apparatus of the character hereinafter described and claimed.

For an illustration of one of the various embodiments of my invention, reference is to be had to the accompanying drawings, in which:

Fig. 1 is an elevational view of control apparatus embodying my invention.

Fig. 2 is a plan view of the same and in addition a plan view of switch structure controlled thereby.

Fig. 3 is an end elevational view of the switch structure.

Fig. 4 is a side elevational view of the same.

Fig. 5 is a diagrammatic view of one of various forms of car driving and controlling systems to which my invention is applicable.

Fig. 6 is a fragmentary plan view, partly in section, of part of the structure of Fig. 5.

Fig. 7 is a diagrammatic view of one of various circuit arrangements with which my invention is utilizable.

Referring to Figs. 1 to 4 inclusive, 1 is a base upon which are carried the posts or standards 2 provided with bearings 3 for

the shaft 4 upon which is secured the sheave or wheel 5, over which passes the safety cable 6. Upon the shaft 4 is secured the bevel gear 7 meshing with and driving the bevel gear 8 secured upon the governor shaft 10 having a bearing 9 carried by one of the posts 2, through which it extends vertically. At the upper end of the governor shaft 10 there are pivoted at 11 the arms 12, 12 carrying at their outer ends the governor balls or weights 13, 13. Pivoted to the arms 12 at 14, 14 are the links 15, 15, pivoted at 16, 16 to the sleeve 17 movable longitudinally of the shaft 10. Co-acting with the sleeve 17 is the non-rotating collar 18 movable longitudinally of the shaft 10 with the sleeve 17. Pivoted to the collar 18 at 19 is the lever 20, to which is pivoted at 21 the link 22 pivoted at 23 to a stationary member, as the post 2. Pivoted to the lever 20 at 24 is a link 25 pivoted at 26 to a lever member 27 secured upon the shaft 28 and having the arcuate slot 29, through which extends a pin 30 for actuating the arm 31, loosely pivoted upon the shaft 28 and having at its upper end the weight 32. Parallel to the shaft 28 is disposed the shaft 33, upon which is disposed the pinion or toothed wheel 34 meshing with the pinion or toothed wheel 35, which latter moves in fixed relation with the arm 31 and the eccentric cable clamping member 36, between which and the opposing eccentric cable clamping member 37 actuated by the pinion 34 may be gripped the safety cable 6.

The link 38, pivoted to the lever 20 at 39, is pivoted at 40 to the lever 41 secured upon the shaft 42 and having the arcuate slot 43, through which extends a pin 44 connected to the arm 45, loosely pivoted upon the shaft 42 and carrying at its upper end the weight 46. Attached to the arm 45 is the eccentric cable-engaging clamp 47, opposed to which is a similar cable-engaging clamp 48 disposed upon the shaft 49 and movable with the toothed wheel or gear 50, driven by the toothed wheel or gear 51 rotated with the arm 45 and the clamping member 47.

The lever 20 and parts connected thereto constitute a weight system opposing upward movement of the sleeve 17 and thereby opposing the outward movement of the balls 13 under the influence of centrifugal

force when the shaft 10 is rotating. However, additional weighting means, as 52, may be carried by the lever 20, on either side of the pivot 19, as may be suitable or desirable.

The weight system described constantly opposes the centrifugal force acting upon the fly balls 13, and thereby operates as a control as regards the upward movement of 10 the sleeve 17 and all the parts controlled or actuated thereby through the links 25 and 38.

Surrounding the governor shaft 10 is a helical spring 53, disposed between the 15 sleeve 17 and a collar 54, which is secured to the shaft 10 at any suitable position longitudinally thereof. As indicated, the collar 54, with the governor structure at rest, as shown in Fig. 1, is disposed at some 20 distance above the upper end of the spring 53, with the result that the spring 53 only after predetermined range of upward movement of the sleeve 17 comes into engagement with the collar 54, and thereafter operates with the weight system in control 25 of the governor, as in opposing the centrifugal force exerted upon the fly balls 13.

Referring to Figs. 2, 3 and 4, there is shown mounted upon the base 1 the slab 30 55, of slate or other suitable insulating material, upon which are mounted two electric switch structures S and S¹. The switch structure S comprises the movable contact 56 pivoted at 57 and engaging the stationary contact 58. Similarly, the switch structure S¹ comprises the stationary contact 59, with which co-acts the movable contact 60 pivoted at 61. Secured upon the shaft 42 is the cam 62 which 35 controls the arm of the switch S pivoted at 57. A second cam 63, secured upon the shaft 42, similarly controls the arm of the switch S¹ pivoted at 61.

Referring now to Fig. 5, C represents the 45 elevator car, to which is attached the main cable 64 driven by any suitable means, as for example, the motor M, Fig. 7, and passing over the sheave or drum 65. Attached to the cable 64 is the counterweight structure W. The safety cable 6 passes over the sheave 5, as aforesaid, and also over the sheaves 66, the cable 6 running adjacent both the car and the counterweight. The sheave 66 is mounted, in any desired manner, at the bottom of the elevator shaft. Upon the bottom of the car C is disposed the rotary drum 67, to which is secured, as at 68, one end of a cable 69 passing around the drum 67 and over idlers 70 and 71 and secured at 72 to the safety cable 6. The drum 67 is secured upon shaft 73 threaded in a tapering or conical nut member 74 disposed between the levers 75, 75 pivoted at 76, 76, Fig. 6, and terminating in short ends 65 77, 77 disposed on opposite sides of the web

of a T-bar 78 paralleling the path of travel of the car C and counterweight W. A second nut 74 and co-acting structure is provided along with a second T-rail 78.

Similar structure is provided upon the 70 counterweight structure W for co-acting with similar rails 78, 78 extending parallel to the path of travel of the counterweight.

Referring to Fig. 7, 79 and 80 indicate supply circuit conductors for supplying current to an electric motor for driving the main cable 64 and attached and co-acting parts. It will be understood that the motor may be of either direct or alternating current type. In the example illustrated, the 80 motor M is of the direct current type having armature A and shunt field windings F, F¹. A relay, having the winding 81 connected across the supply conductors 79 and 80 through the aforesaid switch S, is provided with the movable contact member 82, which, when the winding 81 is energized when the switch S is closed, bridges the contacts 83, 83, thereby bringing into circuit with one section F of the shunt field winding a resistance 84 practically equal to the 90 resistance of the shunt field winding F¹. When the switch S opens, the relay is de-energized and the contact member 82 falls and bridges contacts 85, 85, thereby breaking the circuit through the resistance 84 and bringing the field winding F¹ into circuit in its place, whereby the field of the motor M is strengthened, causing it to tend to run at lower speed.

The armature A is connected between the supply conductors 79, 80 through the contact member 86 bridging the contacts 87, 87 when the relay winding 88 is energized, which it is when the switch S¹ is closed, 105 whereby the winding 88 is connected across the supply conductors 79, 80. When the switch S¹ opens, the contact member drops, thereby completely shutting off current from the motor M, which therefore ceases to deliver power.

It will be understood that the controls illustrated in Fig. 7 are in addition to the usual starting and stopping controls for the motor M.

It will further be understood that an 115 alternating current motor may be employed, in which case analogous controlling means will be employed, comprising means for slowing the motor and means for completely deenergizing it.

The operation is as follows:

As the car C is operated, the governor shaft 10 will be rotated by the safety cable 6 which is pulled along by the car and counterweight structures, since their drums 67 are to some extent restrained against rotation, as by a pawl or like means 89 engaging in the serrated edge 90 of drum 67. Such longitudinal movement of the cable 6 130

rotates the sheave 5, which in turn rotates the governor shaft 10 at a speed corresponding to the speed of the car or counterweight.

For a low range of speed, the spring 53 is inoperative, the weight system only opposing upward movement of the sleeve 17 as effected by the outward movement of the fly balls 13 under the influence of centrifugal force incident to their speed of rotation.

10 As the sleeve 17 rises, however, the upper end of the spring 53 approaches the collar 54, and upon further increase of speed the spring 53 engages the collar 54, and any further increase of speed with accompanying 15 further outward movement of the balls 13 is resisted by compression of the spring 53 between the collar 54 and sleeve 17, such resistance operating cumulatively with the resistance offered by the weight system.

20 If the car attains a predetermined speed above normal or desired speed, the sleeve 17 will have been moved upwardly by the fly balls 13 a corresponding distance, causing corresponding upward movement of the link 38, with resultant corresponding degree of 25 rotation of the shaft 42 sufficient to cause the cam 62 to have its portion of greatest radius removed from beneath the pivoted lever of the switch S, whereupon the mov-

30 able member of the switch S will under the influence of gravity rotate in counterclockwise direction about its pivot 57, as viewed in Fig. 3, causing the movable contact 56 to separate from the stationary contact 58 and 35 thereby deenergize the relay winding 81, whereupon the second field winding F¹ of the motor M is brought into circuit, thereby strengthening the field and reducing the motor speed, or bringing the speed of the 40 car back within predetermined or normal limits.

If, notwithstanding the opening of the switch S, the car speed increases, or has attained an abnormally high speed which is 45 not sufficiently reduced by opening of the switch S, the governor sleeve 17 will have risen higher than previously assumed, causing further upward movement of the link 38 and further rotation of the shaft 42 to 50 extent sufficient to cause the part of greatest radius of the cam 63 to be withdrawn from the movable member of the switch S¹, whereupon the switch S¹ will also open, completely deenergizing the motor M.

55 Or upon even greater excess speed on the part of the car, as when the car is descending at excessive speed, the sleeve 17 and link 38 will have been moved to such extents that the pin 44 will have been actuated by the 60 member 41 and carried to position to bring the weight 46 above and to the right, Fig. 1, of the center of the shaft 42, whereupon the weight 46 will fall toward the right, causing the eccentric clamping member 47 and 65 the co-acting clamping member 48 driven

through the gears 51 and 50 to grip the safety cable 6 and prevent its further downward movement in the direction of the arrow on the right side of the center of the sheave 5, Fig. 1, thereby causing the cable 70 69 to rotate the drum 67 and cause nut members 74 to actuate the levers 75 to cause their ends 77 to pinch and grip the T-bars 78, and so arrest the car C.

Or if the car C is ascending too rapidly, 75 or if the counterweight structure W is descending too rapidly, upon attainment of correspondingly high speed by the governor shaft 10, the link 25 will move downwardly sufficiently to cause the lever 27 so to act 80 upon the pin 30 as to move the weight 32 from the left toward the right across the center of shaft 28, whereupon the cable grip 36, and its companion grip 37, actuated through gears 35 and 34, will grip the cable 85 6, which in such case is descending in the direction of the arrow on the left side of the center of the sheave 5, Fig. 1. This arrests the cable 6 and causes the drum 67 on the counterweight structure W to be rotated, 90 forcing the nuts 75 outwardly and causing the lever ends 77, 77 to pinch and grip the T-bars 78, and so arrest the descent of the counterweight structure.

In accordance with my invention, therefore, at attainment of a predetermined speed, as a speed above normal, the driving motor is controlled in such way as to cause it to rotate or tend to rotate at slower speed; thereafter, at higher speed, the driving motor is 100 completely deenergized; and thereafter, at higher speed, either on the part of the car or counterweight, or both, either the car and counterweight safety device, or both safety devices, are brought into action.

105

In accordance with my invention, the action of the centrifugal or fly ball governor is opposed both by weight, which acts throughout the entire speed range, and also by a spring which comes into action only 110 when a predetermined speed has been exceeded. By this double action of weight system and spring or resilient system, the range of movement of the governor sleeve 115 which effects the controls can be made such as to carry out various successive controls, such as above enumerated, or some of them, since with the weight system alone acting, the governor sleeve may partake of a relatively great range of movement before the 120 first control is effected, that is, before the driving motor is slowed; and within this first part of the entire range of movement of the governor sleeve the control is more sensitive. When, however, with still greater speeds the spring or resilient system comes into action in addition to the weight system for the second range of governor sleeve movement, the action is less sensitive and the 125 operation of completely deenergizing the 130

motor occurs at a more definitely determinable speed, since with the spring in action the governor at the higher speeds is no longer unstable, but is stable. And for still 5 higher speeds the governor continues to be stable, and may accordingly at substantially definite higher speed set into action one or more of the safety cable grips or safety device releases. Such control at substantially 10 definite speeds has been difficult, if not impossible, with governor structures previously employed, so far as I am aware. By employing only the weight system control for the governor mechanism for the lower speed 15 range, that range is of sufficient extent readily to permit control of the field switch or other means for slowing the driving motor, at any one of quite a number of different speeds. For higher speeds, when the spring 20 or resilient system comes into operation, additional controls are possible, and with a nicety of determination as to speed which is not possible with a governor mechanism controlled only by a weight system, which 25 at the higher speeds tends to oscillate or is unstable. In accordance with my invention, the spring or resilient control stabilizes the governor, especially in the highest speed range.

30 By adjustment of the collar or abutment 54 to different positions upon the governor shaft 10 is determined the speed at which the spring 53 begins to co-act with the weight system.

35 Though my invention is not limited thereto, it is preferred that at least the first control, as the slowing of the driving motor, shall be effected during the speed range in which the weight system alone is acting 40 upon the governor, and thereafter, for the speed range within which both the weight system and spring co-act in controlling the governor, the remaining controls are effected.

45 What I claim is:

1. Elevator control mechanism comprising a governor having a member movable in response to changes of speed, a weight system controlling said governor throughout 50 a low speed range, a control device controlled by said movable member, a spring co-acting with said weight system in controlling said governor in a higher speed range, and a second control device controlled by 55 said movable member within said higher speed range.

2. Elevator control mechanism comprising a governor having a member movable in response to changes of speed, a weight system 60 controlling said governor throughout a low speed range, a control device controlled by said movable member, a spring co-acting with said weight system in controlling said governor in a higher speed range, and a plurality of control devices 65

controlled by said movable member and brought into operation in succession in said higher speed range.

3. Elevator control mechanism comprising a governor having a member movable in response to changes of speed, a weight system controlling said governor, a resilient system controlling said governor for speeds in excess of a predetermined speed, a car-operating motor, and motor control switches controlled in succession by said movable member upon attainment of different speeds, one of said switches being actuated after said resilient system has been rendered effective.

4. Elevator control mechanism comprising a governor having a member movable in response to changes of speed, a weight system controlling said governor, a resilient system controlling said governor for speeds in excess of a predetermined speed, a car-operating motor, motor control switches controlled in succession by said movable member upon attainment of different speeds, and a safety device controlled by said movable member upon attainment of a said excess speed.

5. Elevator control mechanism comprising a governor having a member movable in response to changes of speed, a weight system controlling said governor, a resilient system controlling said governor for speeds in excess of a predetermined speed, a car-operating motor, motor control switches controlled in succession by said movable member upon attainment of different speeds, and safety devices for the car and its counter-weight brought into action by said movable member at a said excess speed.

6. Elevator control mechanism comprising a governor having a member movable in response to changes of speed, a weight system controlling said governor through a low speed range, a spring co-acting with said weight system in controlling said governor in a higher speed range, a car-operating motor, a motor control switch controlled by said movable member in said lower speed range, and a second motor control switch controlled by said movable member in the higher speed range.

7. Elevator control mechanism comprising a governor having a member movable in response to changes of speed, a weight system controlling said governor through a low speed range, a spring co-acting with said weight system in controlling said governor in a higher speed range, a car-operating motor, a motor control switch controlled by said movable member in said lower speed range, a second motor control switch controlled by said movable member in the higher speed range, and a safety device brought into action by said movable member after control of said second motor control switch.

8. Elevator control mechanism comprising a governor having a member movable in response to changes of speed, a weight system controlling said governor through a low speed range, a spring co-acting with said weight system in controlling said governor in a higher speed range, a car-operating motor, a motor control switch controlled by said movable member in said lower speed range, a second motor control switch controlled by said movable member in the higher speed range, and safety devices for the car and its counterweight brought into action by said movable member after control of said second motor control switch. 15
9. Elevator control mechanism comprising a safety cable moving with the elevator car, a centrifugal governor driven by said cable, a weight system controlling said governor in a low speed range, a spring coming into action in a higher speed range to control said governor, and control devices brought into action successively by said governor for speeds lying within said low and higher speed ranges. 20
10. The combination with an elevator car and a counterweight therefor, of guide rails for the car and the counterweight clamps carried by the car and the counterweight, respectively, and adapted to grip the rails, a safety cable normally movable synchronously with the car, connections between said cable and the clamps, and means whereby upon a too rapid movement of the car in one direction the movement of said cable is retarded to effect actuation of the clamps which are attached to the counterweight and whereby upon too rapid movement of the car in the opposite direction the clamps carried by the car are actuated. 25
11. The combination with an elevator and an electric motor for driving the same, of control mechanism comprising a governor having a member movable in response to changes of speed and actuated upon movement of the elevator, a weight system controlling said governor, a resilient system controlling the said movable member through but a portion of its path of movement, and a control device for the motor actuated by the said movable member after said resilient system has been rendered effective. 30
12. The combination with an elevator and an electric motor for driving the same, of control mechanism comprising a governor having a member movable in response to changes of speed and actuated upon movement of the elevator, a weight system controlling said governor, a resilient system controlling the said movable member
- through but a portion of its path of movement, and a circuit interrupting device for the motor actuated by the said movable member after said resilient system has been rendered effective. 65
13. Elevator control mechanism comprising a centrifugal governor, a member movable by said governor in response to changes of speed, an operating motor, a motor control switch actuated by said movable member at a predetermined point in its path of movement, and a resilient system for controlling said governor only at speeds in excess of a predetermined rate, whereby the rate of speed of the governor at which the said switch will be actuated may be definitely fixed. 70
14. Elevator control mechanism comprising a centrifugal governor, a member movable by said governor in response to changes of speed, an operating motor, two motor control switches respectively actuated by said movable member at predetermined points in its path of movement, to first reduce the speed of the motor and to then interrupt the circuit therethrough, and a resilient system for controlling said governor only at speeds in excess of a predetermined rate, whereby the rate of speed at which one of said switches will be operated may be definitely fixed. 80
15. Elevator control mechanism comprising a centrifugal governor, a member movable by said governor in response to changes of speed, an operating motor, a motor control switch actuated by said movable member at a predetermined point in its path of movement, a resilient system for controlling said governor at only speeds in excess of a predetermined rate, and means for adjusting the position of said system relatively to the said movable member. 95
16. The combination with an elevator and an electric motor for driving the same, of control mechanism comprising a governor having a member movable in response to changes of speed and actuated upon movement of the elevator, a control device actuated by said movable member during a comparatively low speed range, for reducing the speed of the motor, a control device for interrupting the circuit through the motor and actuated by the said movable member during movement thereof in a high speed range, and a resilient system for controlling the said movable member only during its movement in said high speed range. 105
- In testimony whereof I have hereunto affixed my signature this 26 day of April, 1921. 110
- WILLARD S. ATKINSON. 115
